GEYZA TÓTH, OF NEW YORK, N. Y.

ELLIPSOGRAPH.

1,188,117.

Specification of Letters Patent. Patented June 20, 1916.

Application filed December 7, 1915. Serial No. 65,513.

To all whom it may concern:

Be it known that I, GEYZA TÓTH, a subject of the King of Hungary, and a resident of the city of New York, in the county of New York and State of New York, have invented certain new and useful Improvements in Ellipsographs, of which the following is a specification.

The present invention relates to a scriber 10 designed for producing curved lines, more particularly ellipses.

One of the objects of the invention is to provide an ellipsograph that is simple in construction, efficient in operation, and 15 which can be manufactured on a commercial scale, or in other words which is not so difficult to produce as to be beyond the reasonable cost of such a contrivance.

Another object of the invention is to devise 20 an ellipsograph of this type, upon which can be mounted pencil-, ink-, and other marking members.

A still further object of the invention is to provide a device of the type mentioned 25 which is extremely simple to use, and adjustable for describing ellipses of different sizes and forms.

With these and other objects in view, which will more fully appear as the nature 30 of the invention is better understood, the same consists in the combination, arrangement and construction of parts hereinafter fully described, pointed out in the appended claims and illustrated in the accompanying drawings, it being understood 35 that many changes may be made in the size and proportion of the several parts and details of construction within the scope of the appended claims without departing 40 from the spirit or sacrificing any of the advantages of the invention.

One of the many possible embodiments 45 of the invention is illustrated in the accompanying drawings, in which:—

Figure 1 is a vertical longitudinal section taken through an ellipsograph constructed in accordance with the present invention; Fig. 2 is a top plan view thereof; Fig. 3 is a top plan view of a detail of construction; Fig. 4 is a section taken on line 4—4 of Fig. 1; and Fig. 5 is a diagram illustrating the mode of operation of the apparatus.

In the drawings, the numeral 10 indicates a standard, provided at its lower end with a centering point 11, and at its

upper end with a knob 12, the face 13 of which is milled for a purpose which will appear hereinafter. This standard may be of any suitable cross section, for instance, 60 as shown in the drawings, of circular cross section, and has fixedly attached thereto a spur gear 14. This gear is provided with a downwardly extending sleeve 15, bearing against a washer 16, the latter abutting 65 against a disk-shaped stop 17, that is fastened, for instance, by means of a pin 18 to the standard 10. The gear 14 is secured to said standard, for instance by a pin 19, the latter passing through the sleeve 70 15 and the said standard. Upon the sleeve 15 is slidably and rotatably mounted a horizontally disposed bar 20, that is provided with a downwardly projecting slotted extension 21, the said extension resting upon the washer 16, and its top edge abutting against the hub 22 of the gear 14. The sleeve 15 of said gear is seated in the slot of the extension 21, the width of the slot being substantially of the size of the outer 80 diameter of the said sleeve. With the gear 14 meshes a pinion 23, the ratio between the circumferences of the gear and pinion being, for a purpose hereinafter to be explained, 2:1. This pinion is disposed 85 above the bar 20, and is connected therewith by means of a lug 24, the latter being made in the form of a screw, that extends through the said bar and projects through a somewhat curved, substantially radially 90 extending slot 25 in the pinion 23. The upper end of this screw is seated in an aperture 26, that is formed in one of the legs of a substantially V-shaped member 27, more particularly near the outer end of said leg. 95 This member is shiftably disposed in a recess 28 in the upper face of the pinion 23, and is pivoted at 29 to the said pinion, the pivot 29 extending through the other leg of the member 27 at or near its outer end, 100 and as near to the periphery of the pinion as the structure will permit. Rotation is imparted to the pinion 23 by means of an arm 30, that is provided with an upwardly extending sleeve 31, the latter being drawn 105 over the standard 10, and provided with a milled knob 32. The arm 30 extends a little distance beyond the center of the pinion 23, and has in alinement with the center of said pinion a sleeve 33, that is rotatably arranged in the arm 30. This sleeve is provided with a screw threaded hole 34, the

threads of this hole meshing with those of a clamping screw 35, that is adapted to bear against the upper face of the V-shaped member 27. When this screw is properly screwed down, it holds the V-shaped member 27 in any desired position, and rotates with the pinion 23. The sleeve 33 forms the spindle of the pinion, and the arm 30 the bearing, in which the said spindle is journaled.

10 The bar 20 is provided with a longitudinal slot 36, and in this slot is slidably disposed a split socket 37, into which may be inserted a scribe 38, for instance a pencil, a pen, or any other suitable instrument, as an engraving point, etc. This socket and the scribe carried thereby may be adjusted in relation to the downwardly projecting extension 21, for instance, by means of a screw threaded spindle 39, that is rotatably journaled in the bar, its threads engaging with those of a screw threaded hole 40 in the socket 37. To this spindle is fastened a milled knob 41, that is disposed beyond the 25 outer end of the bar 20.

The operation of this device is as follows: It is to be observed that, if the centering point 11 of the standard 10 is driven in the paper or other surface on which the ellipse 30 is to be drawn or described, and the arm 30 rotated around the longitudinal axis of the said standard, for instance by turning the knob 32, the spur gear 14 will be kept stationary and the pinion 23 will be caused to 35 travel around the circumference of said spur gear and also to revolve on its own axis. In other words, the spur gear 14 forms a sun wheel, and the pinion 23 a planet wheel. It is obvious that the lug 24, or in other 40 words the pivot connecting the bar 20 and the pinion 23, describes, in traveling around the axis of the sun wheel, an epicycloid. Inasmuch as the ratio between the sun wheel and the planet wheel is 2:1, it is obvious that two epicycloids will be described by the lug 24 while the planet wheel makes one complete turn around the circumference 45 of the sun wheel, said planet wheel rotating during such travel twice around its own axis.

50 It is to be observed that with a given setting of the lug 24 in relation to the center of the planet wheel 23, the difference between the major and minor axes of the ellipse is predetermined, the difference being obviously four times the distance of the lug 24 from the center of the planet wheel, or in other words four times the eccentricity of the lug 24. The difference between the two axes of the ellipse to be described can be varied thus by loosening the clamping screw 35, and shifting the V-shaped member 27 around its pivot 29 until the desired eccentricity of the lug 24 has 65 been obtained. After this, the clamping

screw 35 is screwed down to hold the elements fixedly in these positions. In order to describe an ellipse, first of all the split socket 37 with the scribe therein is shifted upon the bar 20 to the desired position. The lug 24 is then brought to the proper position and the clamping screw set to hold it therein. The centering point of the standard 10 is then driven into the surface on which the ellipse is to be drawn, and held 70 against rotation by holding one of the fingers of one hand upon the knob 12. The knob 32 of the arm 30 is then taken hold of by two fingers of the same hand, and the said arm rotated around the center of the 80 gear 14. Let us suppose that, in starting the drawing of an ellipse, the lug 24 is in the position marked in Fig. 5 of the drawings by the numeral I, that is to say it is in the position nearest in relation to the 85 sun wheel 14. When in this position, the marker 38 is located in the major axis 42 of the ellipse. As now the planet wheel turns around the circumference of the sun wheel and revolves around its own axis in 90 the direction of the arrow designated in Fig. 5 of the drawings by the character A, it will be observed that by the time this planet wheel has made one-half of a revolution around its own axis, or in other 95 words a quarter of a turn around the circumference of the sun wheel, the lug 24 arrives at the position denoted by the numeral II, in which it is at its farthest point in relation to the 100 circumference of the sun wheel, and in this position the marker 38 is located in the minor axis of the ellipse. In so traveling the marker describes one-quarter of an 105 ellipse, as clearly shown in Fig. 5 of the drawings, the remaining three-quarters being drawn in the same manner.

Attention is called to the fact that, if the eccentricity of the lug 24 is zero, that is if the axis of the said lug coincides with that 110 of the clamping screw 35, the difference between the major and minor axes will also be zero, or in other words a circle will be described by rotating the arm 30 and the parts connected therewith around the axis 115 of the standard 10.

From the foregoing it appears that with the instrument herein described, not only ellipses of varying sizes can be drawn, but also their focal relation may be predetermined according to the requirements. For varying the size of the ellipse the distance of the split socket 37 must be set in relation to the extension 21, and for varying the focal relation of the ellipse to be drawn, the 120 eccentricity of the lug 24 must be adjusted.

What I claim is:—

1. In an ellipsograph, the combination with a standard having a centering point, of a spur gear rigidly secured thereto, a 130

horizontally extending slotted bar shiftably and rotatably mounted on said standard, a marker carried by said bar, a pinion eccentrically pivoted to said bar and meshing with said gear, and an arm rotatably mounted upon said standard and pivotally connected with the center of said pinion.

5 2. In an ellipsograph, the combination with a standard having a centering point, 10 of a spur gear rigidly secured thereto, a horizontally extending slotted bar shiftably and rotatably mounted on said standard, a

marker carried by said bar, a pinion eccentrically pivoted to said bar and meshing with said gear, an arm rotatably mounted 15 upon said standard and pivotally connected with the center of said pinion, and means for varying, at will, the eccentricity of said pinion.

Signed at New York, in the county of 20 New York, and State of New York, this 20th day of Nov., A. D. 1915.

GEYZA TÓTH.
